ATHLETIC EQUIPMENT SUPPORT RACK
OR SIMILAR ARTICLE

Arden L. Luker, 405 Wisconsin St.,
Sheboygan Falls, Wis. 53085

Filed Nov. 17, 1966, Ser. No. 4,708

Term of patent 14 years

(Cl. D33—3)

FIGURE 1 is a perspective view of an athletic equipment support rack or similar article showing my new design;

I claim:

The ornamental design for an athletic equipment support rack or similar article, as shown.
